(57) CLAIM

We claim the ornamental design for a single-connector cable, as shown and described.

DESCRIPTION

FIG. 1 is a perspective view of a single-connector cable embodying our new design;

FIG. 2 is a front elevation view thereof;

FIG. 3 is a rear elevation view thereof;

FIG. 4 is a side elevation view thereof;

FIG. 5 is another side elevation view thereof;

FIG. 6 is top view thereof; and,

FIG. 7 is bottom view thereof.

The broken line in the figure drawings is included for the purpose of illustrating environment and forms no part of the claimed design.
